COMBINED TOOTH BRUSH RACK AND SOAP CAKE DISPENSER

Adolph K. Stevens, 3346 Washington Blvd., Cleveland
Heights, Ohio, and William F. Delfeld, 1536 Brainard
Road, Lyndhurst, Ohio

Filed Mar. 8, 1961, Ser. No. 64,180

Term of patent 7 years

(Cl. D4—3)

FIG. 1

FIG. 2

FIG. 3

FIG. 4

FIG. 5

FIG. 6

FIG. 1 is a perspective view of a combined toothbrush rack and soap cake dispenser, showing our new design; FIG. 2 is a front elevational view thereof;

FIG. 3 is a top plan view thereof;

FIG. 4 is a bottom plan view thereof;

FIG. 5 is a side elevational view taken from the right of FIG. 1, the opposite side being a mirror image thereof, and

FIG. 6 is a back view thereof.

We claim:

The ornamental design for a combined toothbrush rack and soap cake dispenser, substantially as shown and described.
